US0D1105684S

(12) **United States Design Patent** (10) **Patent No.:** **US D1,105,684 S**
(45) **Date of Patent:** **** Dec. 9, 2025**

(54) **IRONING BOARD**

(71) Applicant: **Jiangmen Vickie Housewares Co., Ltd.**, Jiangmen (CN)

(72) Inventor: **Huixiao Yin**, Guangdong (CN)

(73) Assignee: **Jiangmen Vickie Housewares Co., Ltd.**, Jiangmen (CN)

(**) Term: **15 Years**

(21) Appl. No.: **29/999,176**

(22) Filed: **Apr. 16, 2025**

(30) **Foreign Application Priority Data**

Nov. 25, 2024 (EM) 015083026-0001

(51) **LOC (15) Cl.** **07-05**

(52) **U.S. Cl.**
USPC **D32/66**

(57) **CLAIM**

The ornamental design for an ironing board as shown and described.

DESCRIPTION

FIG. 1 is a front, right and top perspective view of an ironing board, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 2.

FIG. 10 is a rear, left and top perspective view of the ironing board of FIG. 1 shown in another configuration of use.

FIG. 11 is another rear, left and top perspective view of the ironing board of FIG. 1 shown in a folded state; and,

FIG. 12 is another rear, left and top perspective view of the ironing board of FIG. 1 shown in another configuration of use.

The dashed broken lines depict portions of the ironing board that form no part of the claimed design. The dot-dash broken lines in FIGS. 2 and 9 depict the boundaries of the enlarged views and form no part of the claimed design.

1 Claim, 12 Drawing Sheets
